UNITED STATES PATENT OFFICE.

WILLIAM A. LORENZ, OF HARTFORD, CONNECTICUT, ASSIGNOR, BY MESNE ASSIGNMENTS, TO THE NOISELESS TYPEWRITER COMPANY, OF MIDDLETOWN, CONNECTICUT, A CORPORATION OF CONNECTICUT.

TYPE-WRITING MACHINE.

1,082,538.

Specification of Letters Patent.

Patented Dec. 30, 1913.

Application filed April 16, 1909. Serial No. 490,209.

To all whom it may concern:

Be it known that I, WILLIAM A. LORENZ, a citizen of the United States, residing at Hartford, in the county of Hartford and State of Connecticut, have invented certain new and useful Improvements in Type-Writing Machines, of which the following is a full, clear, and exact description, such as will enable others skilled in the art to 10 which it appertains to make and use the same.

This invention relates to typewriting machines, and one of the objects thereof is to provide new and improved means for ar- 15 resting the movements of various operative parts thereof in a silent manner.

Another object is to provide mechanism designed to reduce to a minimum impact or concussion of moving parts during the op- 20 eration of the machine.

Other objects will be in part obvious and in part pointed out hereinafter.

The invention accordingly consists in the features of construction, combinations of 25 elements and arrangement of parts which will be exemplified in the construction hereinafter set forth, and the scope of the application of which will be indicated in the following claims.

30 In the accompanying drawings, wherein is illustrated several of various possible embodiments of the invention, Figure 1 represents a front view of the preferred embodiment of the invention; Fig. 2 is a sectional view thereof on line 2-2 of Fig. 1; Fig. 3 is a view of certain parts of Fig. 1 in another position; Fig. 4 is a view in front elevation of a different embodiment of the invention; Fig. 5 is a side view thereof; Fig. 6 is a 35 view in front elevation of still another embodiment of the invention; and Fig. 7 is a side view thereof.

Similar reference characters refer to similar parts throughout the several figures of 40 the drawings.

Referring now to the drawings, and particularly to Figs. 1 to 3, 1 represents a portion of the framing of the machine the side walls of which are provided with pivot 45 screws 2 which carry a universal rock shaft 3 from which extend arms 4. These arms, by means of links 5, support the universal bar 6 upon which rest the several key levers 7, the latter being pivoted upon a bar 8 and held upwardly by means of coil springs 10

against the stop 11. The universal bar 6 is held against the lower surfaces of the keys 7 by means of a coil spring 12 which extends between a fixed portion of the machine and an arm 13 extending from the universal rock 60 shaft 3. The universal bar at its central portion is provided with depending ears 15 between which extends a stud 16, said stud, in the present instance, carrying rollers 17 and 18.

65 A cross brace 20 supports, by means of a clamp screw 21, a vertically adjustable bracket 22. This bracket is provided with a projecting ear 23 which bears against the roller 17 and is also provided with two studs 24 and 25 each of which supports a roller 26. Upon rollers 26 is positioned an endwise movable slide 27 provided with suitable slots 28 for receiving the rollers 26. Slide 27 is provided with a pin 30 to which the 70 coil spring 31 is attached, the other end of said spring being secured to a post 32 extending from bracket 22. Slide 27 is provided with a projecting portion or finger 33 and also with a concaved surface 34, roller 18 of the universal bar normally bearing against said projecting portion 33, as shown in Figs. 1 and 2. The cam surface 34 is struck from an arc of larger radius than that of the roller 18, and the radius of the 75 cam surface gradually decreases in a downward direction.

80 Having thus described the construction of this embodiment of my invention, the operation thereof may now be understood. When the universal bar is depressed by a key lever to be moved from the position shown in Fig. 1 to that in Fig. 3, the roller 17 will roll against the face of projection 23, and the roller 18 will roll against the face 85 of projection 33. The face of projection 23 is made vertical in order that the travel of the universal bar may be in a straight line and said part therefore acts as a guide for the universal bar during its downward movement. The face 35 of projection 33 may be made vertical or slightly inclined. The universal bar continuing its downward movement engages the cam surface 34 and moves the cam slide sidewise until the roller 90 strikes the lowermost portion thereof when the universal bar will be brought to a gradual stop, the stopping thereof being effected without noise. It will be understood, of course, that the endwise movement of the 95 100 105 110 115

slide is opposed by the spring 31. When the pressure upon the key lever is released the universal bar will return to its normal position, spring 31 constantly holding the 5 cam surface in contact with roller 18, thereby assisting in moving the universal bar to such normal position. Slide 27 as shown herein moves at right angles to the direction of movement of the universal bar, but 10 if desired this slide may be set at a different angle.

In the embodiment of my invention shown in Figs. 4 and 5 the universal bar 6 is provided with rollers 17 and 18 mounted upon 15 the stud 16. The brace 20 is provided with the vertically adjustable bracket 22 which is provided with two slides 36 and 37, one slide being provided with a projecting portion 38 and a curved cam portion 40, and 20 the other with a projecting portion 41 and a similar cam portion 42. These two slides are provided with projecting ears 43 connected by a retractile coil spring 44. When the universal bar is moved downward 25 the roller 17 will roll against the projection 38 and cam surface 40 and the roller 18 will roll against the projection 41 and cam surface 42. Upon reaching the downward position the two slides 36 and 37 will be separated 30 and the universal bar will be gradually brought to a stop.

In the embodiment of the invention shown in Figs. 6 and 7 the universal bar is provided with a downward projecting guide piece 45 35 having a vertical face 46 on one side for its entire length, and having a flat face 47 on the opposite side for a portion of its length, said flat portion merging into a curved face 48 above the vertical face. To the brace 20 40 is attached a vertically adjustable bracket 50 which supports the roller 51 against which the vertical face 46 rides. The bracket 50 also supports, as by means of rollers 52, the slide 53, said slide being provided with a 45 roller 54 which normally bears against the face 47 of guide 45. A spring 55 extending between the slide and the bracket urges roller 54 into engagement with the face 47 of guide 45. When the moving 50 member or universal bar is moved downward, no resistance is offered except the spring pressure exerted upon the slide 53 until the universal bar reaches a position near the end of its downward movement, 55 when the motion of the moving member will be gradually resisted by means of the cam face 48, and such motion will ultimately be arrested by the cam surface when the horizontal portion of said surface shall have 60 been engaged by the roller.

It will accordingly be seen that I have provided mechanism of the above character well adapted to attain among others all the ends and objects above pointed out in a simple yet efficient manner. The elimination 65

of concussion or impact between the moving parts insures a silent operation, and the rolling contact between the rollers and the cam surfaces reduces friction to a minimum, insuring a ready and quick respond of the universal bar to the touch of the operator, or to movement impelled by the spring-controlled cam or roller devices when the pressure is removed from the key levers.

While I have shown and described my invention applied to the universal bar of a typewriting machine, I wish it to be understood that I do not intend to limit its employment to these precise relations, as the same is capable of use in a variety of relations in machines of this, as well as those of other types.

As many changes could be made in the above construction and many apparently widely different embodiments of this invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. The combination with a movable part 95 of a typewriting machine, of means for arresting the movements thereof without impact or concussion comprising a fixed member for guiding the movable part, and a reciprocating member having a cam portion 100 engaging the movable part.

2. The combination with a movable part of a typewriting machine, of means for arresting the movements thereof without impact or concussion comprising a fixed member which operates to guide the movable member, a reciprocating member having a cam surface, and means located upon the movable member adapted to traverse said cam surface when the movable part is actuated.

3. The combination with the movable part of a typewriting machine, of means for arresting the movements thereof without impact or concussion comprising a fixed part, a 115 roller mounted on one of said parts, a member having a cam surface mounted to slide upon the other of said parts, and spring means for holding said cam surface and said roller in constant engagement.

4. The combination with the movable part of a typewriting machine, of means for arresting the movement thereof without impact or concussion comprising a slidable part, a roller carried by one of said parts, a cam member carried by the other of said parts, and spring means for maintaining a constant engagement between said roller and said cam member.

5. The combination with the movable part 130

of a typewriting machine of means for arresting the movement thereof without impact or concussion comprising a fixed guide part, a second part movable relatively thereto, and a roller, one of said elements being carried by said first movable part and another by the fixed part.

6. The combination with a movable part of a typewriting machine, of means for arresting the movements thereof without impact or concussion comprising a fixed part, a relatively movable sliding cam and roller mechanism, one portion of which is mounted upon the movable part and the other thereof upon the fixed part, and spring means coöperating with said cam and roller mechanism to oppose a relative movement thereof.

7. The combination with a movable part of a typewriting machine, of means for arresting the movements thereof without impact or concussion comprising a fixed part, a relatively movable sliding cam and roller mechanism one portion of which is mounted upon the movable part and the other thereof upon the fixed part, spring means coöperating with said cam and roller mechanism to oppose a relative movement thereof, and means for guiding said movable part.

8. The combination with the movable part of a typewriting machine, means for arresting the movements thereof without impact or concussion comprising a fixed part, a member having a concave cam surface mounted on one of said parts and adapted to slide thereon, a roller carried by the other of said parts engaging said cam surface, and spring means for holding said roller and cam surface in constant engagement.

9. The combination with the movable part of a typewriting machine, of means for arresting the movements thereof without impact or concussion comprising a fixed part, means upon the fixed part for causing said movable member to move along a straight line, a member provided with a concave cam surface carried by the fixed part and adapted to slide thereon, means carried by the movable part for traversing said cam surface, and spring means for holding said last-mentioned means and said cam surface in constant engagement.

10. The combination with a movable part of a typewriting machine, of means for arresting the movements thereof without impact or concussion comprising a roller carried by the movable part, a member mounted to reciprocate upon the fixed part having a concavely formed cam-path, said roller being adapted to traverse said cam-path during the movement of said movable part, whereby the member provided with the cam-path will be moved endwise, and spring means interposed between the roller and said reciprocating member for maintaining

the cam-path of the latter in constant engagement with said roller.

11. The combination with a movable part of a typewriting machine, of means for arresting the movements thereof without impact or concussion comprising a fixed part, a member rotatably mounted upon one of said parts, a member slidably mounted upon the other of said parts, and means for holding said members in constant engagement.

12. The combination with a movable part of a typewriting machine, of means for arresting the movements thereof without impact or concussion comprising a fixed part, a roller mounted upon one of said parts, a reciprocatory cam member mounted upon the other of said parts, and spring means for maintaining a constant engagement between said roller and said cam.

13. The combination with a movable part of a typewriting machine, of means for arresting the movements thereof without impact or concussion comprising a roller carried by the movable part, a cam member mounted to slide upon the fixed portion of the machine, and spring means adapted to hold said cam member in engagement with said roller.

14. The combination with a movable part of a typewriting machine, of means for arresting the movements thereof without impact or concussion comprising a fixed part, a member having a concave cam surface mounted upon the fixed part, means mounted upon the movable part adapted to traverse said cam surface when the movable part is actuated, means for maintaining the means upon the movable part and said cam surface in constant engagement, and means for causing the movable part to move in a straight line.

15. In a typewriting machine, the combination with the universal bar and the key levers which rest thereon, of means for arresting the downward movements of the key levers without impact or concussion comprising a roller journaled on the universal bar, a member mounted to reciprocate upon a fixed portion of the framing of the machine and having a concavely formed cam-path the surface of which is formed upon an arc of decreasing radius, and means for maintaining said roller in constant engagement with said cam-path.

16. In a typewriting machine, the combination with the universal bar and the key levers which rest thereon, of means for arresting the downward movements of the key levers without impact or concussion comprising a roller mounted upon the universal bar, a sliding member having a concavely formed cam-path along each side of the roller, spring means for maintaining the cam portion of said member and said roller in engagement, a second roller mounted

- upon the universal bar, and a fixed guide engaging said last mentioned roller adapted to cause said universal bar to move in a straight line.
- 5 17. The combination with a movable part of a typewriting machine, of means for arresting the movements thereof without impact or concussion comprising a fixed part, cam means upon one of said parts adapted 10 to be moved in a direction substantially at right angles to the direction of the movement of the movable part, means upon the other of said parts for traversing said cam means, and spring means for holding said 15 cam means and said traversing means in constant engagement.
18. In a typewriting machine, the combination with the universal bar and the key levers which rest thereon, of means for arresting the downward movements of the key levers without impact or concussion comprising a roller journaled upon the universal bar, a sliding member provided with a concave cam surface carried by a fixed portion of the machine, the cam surface of which is formed upon an arc of decreasing radius, a roller carried by the universal bar adapted to traverse said cam surface when the universal bar is depressed, a spring for 25 maintaining said cam surface and said roller in engagement, a second roller carried by the universal bar, and a guide carried by a fixed portion of the framing of the machine and engaging said last mentioned 30 roller, whereby said universal bar is caused to move in a straight line when depressed.
19. In a typewriting machine, the combination with the universal bar and the key levers which rest thereon of means for arresting the movement of the key levers when depressed comprising a roller mounted upon the universal bar, a member provided with a concavely formed cam surface adapted to reciprocate upon a fixed portion of the 40 machine, a spring for maintaining said cam surface and said roller in engagement, a second roller carried by the universal bar, and a guide carried by a fixed portion of the machine which engages said last mentioned 45 roller and thereby causes the universal bar to move in a straight line when depressed.
20. In a typewriting machine, the combination with the universal bar and the key levers which rest thereon, of means for arresting the movements of the key levers when depressed comprising a roller mounted upon the universal bar, an endwise movable member provided with a concavely formed cam surface, a bracket mounted upon the 55 fixed portion of the machine in which said member may be slid, a spring for maintaining the cam surface of said member and said roller in constant engagement, a second
- roller mounted upon the universal bar, and a guide extending upward from said bracket 60 and engaging said second roller adapted by such engagement to cause the universal bar to move in a straight line when depressed.
21. The combination with a movable part of a typewriting machine of means for arresting the movement thereof without impact or concussion comprising a reciprocating member having a cam portion engaging said movable part, and means for adjusting one of said parts to change the limit of the 70 path of travel of said movable part.
22. The combination with a movable part of a typewriting machine of means for arresting the movement thereof without impact or concussion comprising a reciprocating member having a cam portion engaging said movable part, and means for adjusting said reciprocating member in the direction of the path of travel of said movable member.
- 85 23. The combination with a movable part of a typewriting machine of means for arresting the movement thereof without impact or concussion comprising a fixed part, a member rotatably mounted upon one 90 of said parts, a member slidably mounted upon the other of said parts, means for holding said members in constant engagement, and means for adjusting said arresting means in the direction of the path of travel of said movable member.
24. The combination with a movable part of a typewriting machine of movable means for silently arresting the movement thereof without impact or concussion, a spring 100 adapted to act on said movable means and means for adjusting said movable arresting means in the direction of the path of travel of the movable part.
25. The combination with a movable part of a typewriting machine, of means for silently arresting the movement thereof without impact or concussion, comprising a relatively fixed guiding member and a co-acting movable cam member adapted to engage the movable member.
- 105 26. The combination with a movable part of a typewriting machine, of means movable at right angles to the direction of movement of the movable part adapted to silently 110 arrest the movement thereof, a spring adapted to act on said movable means and hold the same in normal position, and means for adjusting said movable means with respect to said movable part.
- 115 In testimony whereof I affix my signature, in the presence of two witnesses.
